UNITED STATES PATENT OFFICE

92,437

DESIGN FOR A COOLER FOR DRY AND WET COOLING BOTTLED GOODS

George L. Strebler, St. Louis, Mo., assignor to
Eagle Foundry Company, a corporation of
Illinois

Application March 12, 1934, Serial No. 51,021

Term of patent 7 years

To all whom it may concern:

Be it known that I, GEORGE L. STREBLER, a citizen of the United States, residing in the city of St. Louis and State of Missouri, have invented a new, original, and ornamental Design for a Cooler for Dry and Wet Cooling Bottled Goods, of which the following is a specification, reference being had to the accompanying drawing, forming part thereof.

The figure is a perspective view of a cooler for dry and wet cooling bottled goods, showing my new design.

I claim:

The ornamental design for a cooler for dry and wet cooling bottled goods, as shown.

GEORGE L. STREBLER.
